UNITED STATES PATENT OFFICE.

ALFREDO DIATTO, OF TURIN, ITALY.

CONTACT-BOX FOR ELECTRIC RAILWAYS.

SPECIFICATION forming part of Letters Patent No. 650,929, dated June 5, 1900.

Application filed July 30, 1898. Serial No. 687,322. (No model.)

To all whom it may concern:

Be it known that I, ALFREDO DIATTO, electrical engineer, a subject of the King of Italy, and a resident of Turin, Italy, have invented 5 a certain new and useful Improvement in Contact-Boxes for Electrical Railways or Tramways with Underground Conductors, (for which I have obtained a patent in Italy, dated May 24, 1898, No. 47,039,) of which the following is a specification.

My present invention refers to certain improvements in the contact-boxes of electrical railways or tramways with underground conductors, and has for its object to protect the 15 contact-pieces from becoming wet or damp, and thus avoid leakage of current and other drawbacks occasioned thereby.

The invention is more particularly suitable for that system of electrical railways or tramways with underground conductors described in my United States Patent No. 550,319.

In order that my said invention may be more fully understood, I will proceed to describe same, with reference to the annexed 25 drawing, which is a central vertical section of the inner part of a contact-box comprising my said improvements.

r is the mercury-cup, and near its top it is provided with an annular cup r' , concentric 30 with the extension d of the partial conductor c , which is partially filled with a sealing liquid y . q indicates the mercury contained in the cup r . A bell C' , of any suitable non-conducting material, such as india-rubber, is fitted over and covers the said conductor c , with which it is concentric, and its lower end dips to a suitable extent in the liquid y contained 35 in the annular cup r' , so as to form a hydraulic joint. It will thus be seen that the contact-pieces c d are inclosed in an air-proof 40 space, and are thereby protected against the dampness of the atmospheric air. The bell C' may be provided with an annular rim C^2 to stand over the annular cup r' and protect 45 it from the water that may run down from the bell or the cover of the box k .

The operation of contacts c d of the device hereinabove described is substantially the same as that of the corresponding parts set 50 forth in my prior United States patent hereinabove referred to, and therefore the operation need not be again described here.

The liquid y should be of such nature as

not to be subject to freeze and to be capable of absorbing any air-vapor that may be contained within the bell, and I have found that glycerin answers the purpose very satisfactorily.

It is obvious that the form and arrangement of the various parts may be varied without departing from the gist of my invention and that the same is not limited to the particular form and arrangement described and illustrated.

I claim—

1. In a contact-box for electrical railways or tramways with underground conductors, the combination of a mercury-cup r , mercury therein, a contact-piece extending within the mercury and having an extension projecting 70 above the cup, an annular cup r' on the cup r , concentric with the extension of the contact-piece, a sealing liquid as described contained within the cup r' , a bell C' of non-conducting material arranged over and covering 75 the contact-piece and having its lower end dipping within the liquid in cup r' , and a second contact-piece covered by the bell C' and confined within the closed space of the latter above the first contact-piece, as and for the 80 purpose set forth.

2. In a contact-box for electrical railways or tramways with underground conductors, the combination of a mercury-cup r , mercury therein, a contact-piece extending within the 85 mercury and having an extension projecting above the cup, an annular cup r' on the cup r , concentric with the extension of the contact-piece, a sealing liquid as described contained within the cup r' , a bell C' of non-conducting material arranged over and covering 90 the contact-piece and having its lower end dipping within the liquid in cup r' , a second contact-piece covered by the bell C' and confined within the closed space of the latter 95 above the first contact-piece, and an annular rim C^2 on the bell extending over and beyond the cup r' , all as and for the purposes specified.

In witness whereof I have hereunto set my 100 signature in the presence of two witnesses.

ALFREDO DIATTO.
